UNITED STATES PATENT OFFICE.

EDWARD W. SALMON, JR., OF BALTIMORE, MARYLAND, ASSIGNOR OF ONE-HALF TO
CHRISTIAN H. NELSON, OF BALTIMORE, MARYLAND.

REEL.

1,088,089.

Specification of Letters Patent.

Patented Feb. 24, 1914

Application filed July 31, 1912. Serial No. 712,602.

To all whom it may concern:

Be it known that I, EDWARD W. SALMON, Jr., a citizen of the United States, residing at Baltimore, State of Maryland, have invented certain new and useful Improvements in Reels, of which the following is a specification.

This invention relates to reels.

The reel herein illustrated and described is one particularly adapted for use by me in connection with machines for uniting metallic sheets or plates and subsequent to uniting the same, winding them on the reel.

One object, however, is to provide a reel applicable for winding other material thereon whether in single strips or interlocked strips.

Another object is to provide a reel embodying among other characteristics means whereby material may be wound thereupon and at a predetermined time readily discharged therefrom.

A still further object resides in the provision of a reel embodying the aforesaid characteristics and including means whereby the same may be adjusted for the winding of material of various widths.

With the above and other objects in view the present invention consists in the combination and arrangement of parts hereinafter more fully described, illustrated in the accompanying drawings, and particularly pointed out in the appended claims, it being understood that changes may be made in the form, proportion, size and minor details without departing from the spirit or sacrificing any of the advantages of the invention.

In the drawings: Figure 1 is a front elevation of the invention. Fig. 2 is a side elevation. Fig. 3 is a top plan view.

As has been intimated, my improved reel may be used for various purposes and with this understanding reference to the accompanying drawings will disclose two standards 10 and 11, each having upper and lower bearings 12 and 13, the standard 11 having a foot 14 by means of which it may be fastened or otherwise supported on any suitable base. The standard 10 has a foot 15 adapted to be fixed in adjustable positions by means of bolts 16 on the slide 17 which latter may be fastened or otherwise secured to a suitable base. Thus, the standard 10 may be adjusted toward and away from the

standard 11 for a purpose presently explained.

Journaled in the bearings 12 of the standards 10 and 11 are stub shafts 18 and 19, respectively, on which stub shafts are fixedly mounted at the inner ends thereof disks 20 each provided with a plurality of apertures *a* through which may slide a plurality of fingers, projections, or material retaining elements 21 carried by disks 22 slidably mounted on said stub shafts 18 and 19.

One form of means for effecting a sliding movement of the disks 22 on the stub shafts 18 and 19 resides in attaching to the outer side face of each disk 22 a grooved collar 23 into the groove of each of which project the fingers 24 of the forked arms 25 and 26 of the levers 27 and 28, respectively. The lever 28 is preferably pivotally mounted at 29 on the ear or lug 30 of the standard 11. The lever 27 is preferably pivoted by means of a suitable pivot 31 on the ear or lug 32 of the standard 10. The pivots 29 and 31 are preferably opposite each other and the levers 27 and 28 are arranged so that their inner ends may overlap in spaced relation as clearly shown in Figs. 1 and 3.

To operate the levers 27 and 28 I provide preferably a lever 33 which is preferably mounted on the same pivot 31 as the one on which the lever 27 is pivoted. This operating lever 33 is provided at its inner end with an arm 34 which lies beneath the aforesaid levers 27 and 28 and intermediate its ends it is preferably provided with apertures 35 whereby, in the event of an adjustment of the standard 10 outwardly, these apertures may have fitted in either of them the aforesaid pivot 31 according to the degree of adjustment of the standard 10 away from the standard 11.

To operate the reel for the purpose of winding the material A thereon I provide a drive shaft 36 which is journaled in the aforesaid bearings 13 of the standards 10 and 11. This shaft 36 is connected by chains 37 and sprocket wheels 38 with the aforesaid stub shafts 18 and 19 so that upon rotation of the drive shaft 36 the stub shafts 19, and consequently the reel disks 20 and 22 are operated to wind the material on the material retaining fingers 21 of the reel. To effect rotation of the drive shaft 36 I dispose on the same a pulley 39 to which may be connected a driving belt 41 con-

nected up with any suitable driving source (not shown) to effect a friction drive.

The operating lever 33 may be arranged to be operated either by hand or foot power or in any other suitable manner. Irrespective of how operated, a downward movement on the outer end of the operating lever 33 will cause an upward movement of the inner end thereof and a consequent uniform 10 raising of the levers 27 and 28 by the arm 34 of said lever 33. As the levers 27 and 28 are raised on their pivots 29 and 31 the forked arms 25 and 26 are consequently thrown outward with the result that, by 15 virtue of the connections between the forked arms 25 and 26 with the disks 22, the fingers or material retaining elements 21 are drawn through the apertures *a* of the disks 20 with the result that the material wound 20 upon these material holding fingers 21 is permitted to drop from the reel. I preferably dispose an inclined conveying means 40 of any suitable character beneath the reel for the purpose of taking this wound material which is discharged from the reel to any suitable place. While the sprocket wheel 38 on the shaft 36 adjacent the standard 10 is rotatable with the drive shaft 36 it is slidably mounted thereon so that as 25 the standard 10 is moved longitudinally of the shaft 36 for adjustment purposes, said sprocket wheel may be moved also longitudinally of the shaft 36 according to the adjustment of the standard 10 with respect 30 to the standard 11.

What is claimed is:—

1. A device of the character described comprising spaced standards, a drive shaft journaled in the standards intermediate the 40 ends of the latter, stub shafts journaled in the standards at the upper ends of the latter over the drive shaft, a disk fixedly mounted at the inner end of each stub shaft and provided with apertures, a disk slidably mounted on each stub shaft adjacent the aforesaid disks and provided with material retaining fingers which project through the apertures of the first-named disks, driving connections between the drive 45 shaft and the stub shafts, bell crank levers pivoted on the standards and each having one of its arms connected with one of the first-mentioned disks, another lever pivoted on one of the standards and provided with an arm at one end adapted to engage the other arms of said bell crank levers to operate the latter to throw the second-mentioned disks outwardly on the stub shafts and thereby draw both sets of the material 50 retaining fingers outwardly through the apertures of the fixed disks to discharge the material from the reel.

2. A reel including in combination spaced standards, a drive shaft journaled in the 55 standards above the drive shaft, a disk

fixedly mounted at the inner end of each stub shaft and provided with apertures, a disk slidably mounted on each stub shaft and provided with material retaining fingers which project through the apertures of the first-named disks, driving means between the drive shaft and the stub shafts, levers pivoted on the standards and having operative connection with the second mentioned disks with portions of the levers overlapping each other in spaced relation, means for engaging said levers at their overlapping portions to operate said levers so as to slide the second-mentioned disks on their stub shafts to draw both sets of said material retaining fingers outwardly through the apertures of the first-mentioned disks to discharge the material from the reel.

3. A device of the character described, including in combination, a reel embodying oppositely disposed movable disks and material retaining fingers on which material may be wound, means for rotating the reel, bell crank levers having connection with disks of the reel to operate said disks and thereby disconnect the material retaining fingers from the material wound thereon to effect a discharge of the material from engagement with said fingers, and means for operating said bell crank levers.

4. A device of the character described including in combination, a reel embodying oppositely disposed movable disks and material retaining fingers on which material may be wound, means for rotating the reel, bell crank levers having connection with disks of the reel to operate said disks and thereby disconnect the material retaining fingers from the material wound thereon to effect a discharge of the material from engagement with said fingers, and another lever having an arm at one end adapted to engage the bell crank levers to operate the same upon operation of said other lever.

5. A device of the character described comprising spaced standards, a drive shaft journaled in the standards, stub shafts journaled in the standards above the drive shaft, a disk fixedly mounted at the inner end of each stub shaft and provided with apertures, a disk slidably mounted on each stub shaft and provided with material retaining fingers which project through the apertures of the fixed disks, driving means between the drive shaft and the stub shafts, bell crank levers pivoted on the standards below the drive shaft and each including an upwardly directed arm and an inwardly directed arm, the upwardly directed arms of the bell crank levers being connected to the 110 slideable disks, the inwardly directed arms of the bell crank levers overlapping each other in spaced relation, means for engaging the inner ends of the inwardly directed arms of the bell crank levers to operate the 115

latter and thereby slide the slidable disks away from the fixed disks to thereby draw both sets of said material retaining fingers outwardly through the apertures of the fixed disks to discharge the material from said material retaining fingers.

6. A device of the character described including in combination spaced standards, a drive shaft journaled in the standards, stub shafts journaled in the standards, driving means between the drive shaft and the stub shafts, a disk fixedly mounted at the inner end of each stub shaft and provided with apertures, a disk slidably mounted on each stub shaft and provided with material retaining fingers which project through the apertures of the first-mentioned disks, bell crank levers pivoted on the standards and each including an upwardly directed forked 20 arm having operative connection with the corresponding slidable disk with its other arm projecting inwardly of the standards, the inner ends of the inwardly directed arms of the bell crank levers overlapping in 25 spaced relation, a lever adjustably mounted on one of the standards and having an arm adapted to engage the overlapping ends of the inwardly directed arms of the bell crank

levers to operate the latter and thereby shift the slidable disks on the stub shafts to draw 30 the material retaining fingers outwardly through the apertures of the fixed disks, one of said standards being mounted for adjustment toward and away from the other standard.

7. The combination with spaced standards, of a reel composed of opposite stub shafts on which are fixed opposing fixed disks provided with apertures, disks slidable or the opposing stub shafts and provided with 40 fingers adapted to project through the apertures of the corresponding fixed disks, levers having connection with the slidable disks, and means engageable with said levers to move the slidable disks together outwardly 45 away from each other and away from the fixed disks to draw the fingers thereof outwardly through the apertures of the fixed disks and thereby discharge the material from engagement with said fingers. 50

In testimony whereof I affix my signature in presence of two witnesses.
